(57) **CLAIM**

The ornamental design for a fountain, as shown and described.

DESCRIPTION

FIG. 1 is a perspective view of a fountain showing my new design;

FIG. 2 is a side view of the fountain of FIG. 1;

FIG. 3 is a top view of the fountain of FIG. 1; and,

FIG. 4 is a bottom view of the fountain of FIG. 1.
The broken line showing of a portion of the fountain in FIG. 3 is included for the purpose of illustrating and forms no part of the claimed design.

1 Claim, 2 Drawing Sheets

FIG. 1

FIG. 2

FIG. 3

FIG. 4
